William Blake's Design for a Girandole

Patented 17 Mar. 1843.

Specification & Drawings of R.H. Eddy, Boston.

Des 3

William Blake, Boston Mass. assignor to Henry
A. Hooper & Company - Boston Mass. -

Letters Patent No. 3. Dated March 17. 1843. -

(The Schedule referred to in these Letters Patent and making part
of the same. -

To all Persons to whom these Presents shall come.

Be it known that I, William Blake of Boston in the County of Suffolk
and State of Massachusetts, have invented a new and ornamental
design or pattern for Girandoles, or stands for candles, lamps
or for other purposes: and that the same is fully exhibited by
the accompanying drawing and also in the model or specimen
thereof deposited by me in the Patent Office of the United States.

I do hereby declare that the following description taken
in connection with the drawing above mentioned, will clearly
explain the character of my invention, together with such part
or parts thereof as I claim to be new.

The foot, or part situated between the points a, b, and
which sustains the body or branches of the girandole, rests
upon a rectangular or other proper shaped marble or
metallic base c; and, as the said foot and base are old
in their design and in common use in other articles to which
they have been adapted, they need no further description.

The body or portion of the article comprehended between
the foot or the points a, and the stems or bases or extreme points

of junction of the leaves α , β , γ , δ , δ' of the three candle cups ϵ , ϵ' , (from the points or extremities of which leaves, the glass reflecting prisms are to depend in the usual manner, is that part of the same, which generally speaking, is novel in composition or design. The drawing exhibits a front view of the girandole. The rear side of the body of the same is similar to the front, or it may be hollowed out in the usual manner. The peculiar character of foliage, or imitation of stalks and leaves forming this design, is well known in the arts, and it is their intertwinnings or combination together as exhibited in the drawing, which constitute the beauty as well as the utility of the pattern.

By inspecting the drawing it will be perceived that the body or stand consists of two main branches or stalks $\mathfrak{f}$, $\mathfrak{f}'$, springing in opposite directions from a common point α , their junction being covered by a vertical leaf $\mathfrak{g}$. These branches after being curved somewhat in what may be termed a "harp shape," are joined and connected together, by the volutes $\mathfrak{h}$, $\mathfrak{h}'$, as seen in the drawing, just on their extremities the two lateral candle cups. The central or highest candle cup is sustained by twisted stems proceeding from the junction of two leaves $\mathfrak{i}$, $\mathfrak{i}'$, which spring from the main branches, just above the volutes $\mathfrak{h}$, $\mathfrak{h}'$.

Just in rear of the upper termination of the leaf before described, which covers the union of the main branches at the point α , two honey-suckle flowers $\mathfrak{k}$, $\mathfrak{k}'$, curve upwards in a circle and may be joined together at their tips. These are supported by two volutes $\mathfrak{l}$, $\mathfrak{l}'$, springing from the main branches $\mathfrak{f}$, $\mathfrak{f}'$.

By removing from the main branches $\mathfrak{f}$, $\mathfrak{f}'$ the leaves $\mathfrak{i}$, $\mathfrak{i}'$ and the parts above them which support the central candle cup, the remainder of the design will answer for a girandole of two branches. Should it be desirable to make use of

the design for a candelabrum or any similar purpose, the two exterior or lateral candle-cups, together with those parts of the main branches f. f. situated between said cups and the points m or n may be removed at said points. And in like manner the removal of the leaves i, i and the parts above them, together with those parts of the branches f. f. which extend laterally from or beyond the points m, m, and serve to sustain the candle-cups, the remainder of the pattern may be used for a harp or other purpose to which it may be devoted.

As the drawing which accompanies this description will be found to be sufficient to enable any carver of ordinary skill to fully or substantially comprehend the whole of my design, so as to practically apply the same in this art. I shall now set forth such portions of the design which I claim.

First, I claim the combination of the design of the base or foot, situated below the point a, and that of the body stand or main branches f. f. extending above said point.

Second. I claim the combination of the several parts or composition or design of the stand or main branches, with their leaves and volutes extending above the point a, and also the same as independent of the leaves i, i, and ornamental stems, supporting the central candle cups; by which latter arrangement, the design for a girandole of two branches is effected.

I also claim the design of the stand exclusive of those parts, which project beyond the points m or opening of the leaves thereof, and which support the lateral candle cups, and I also claim the latter arrangement exclusive of the leaves i, i, and ornamental stems situated above the points o, o, and which sustain the central or upper candle cups. The last two arrangements producing the design for a stand of a candelabrum or for a harp or any other purpose to which the same may be successfully applicable.
